Primary Examiner—Ted Shooman*Assistant Examiner*—C. Tuttle*Attorney, Agent, or Firm*—Dorsey & Whitney LLP[57] **CLAIM**

The ornamental design for a valve, as shown and described.

DESCRIPTION

FIG. 1 is a perspective view depicting the valve of the present invention;

FIG. 2 is an elevational view of one side thereof, all sides appearing the same;

FIG. 3 is a top plan view thereof; and,

FIG. 4 is a bottom plan view thereof.

The appearance of the spaces between the upper ribs and the interior portions not shown in the drawings form no part of the claimed design.
